UNITED STATES PATENT OFFICE.

ELMER P. MCCLURE, OF WESTERN SPRINGS, AND JAMES B. LOEWENSTEIN,
OF CHICAGO, ILLINOIS.

CORN-GATHERING MACHINE.

No. 850,390.

Specification of Letters Patent.

Patented April 16, 1907.

Application filed March 10, 1906. Serial No. 305,255.

To all whom it may concern:

Be it known that we, ELMER P. MCCLURE and JAMES B. LOEWENSTEIN, citizens of the United States, residing, respectively, at Western Springs, in the county of Cook and State of Illinois, and Chicago, in the county of Cook and State of Illinois, have invented new and useful Improvements in Corn-Gathering Machines, of which the following is a specification, reference being had to the accompanying drawings, forming a part thereof.

The purpose of this invention is to provide an improved machine for gathering corn, in which for the several processes performed separate suitable mechanisms may be carried by the frame of the machine and operated by power not derived from the traction of the carrying-wheels of the machine, but from a power generator or motor mounted on the frame, the machine being drawn through the field by any convenient means, also to provide for baling the husks in and by the machine by which they are stripped from the ears.

It consists of the features of construction and combinations of mechanism set out in the claims.

In the drawings, Figure 1 is a plan view of a machine embodying our invention. Fig. 2 is a grain-side elevation. Fig. 3 is a section at the line 3-3 on Fig. 2. Fig. 4 is a detail plan view of certain power-transmitting devices.

The structure shown in the drawings has a rigid frame comprising a long and relatively narrow fore-and-aft main portion consisting of suitable fore-and-aft bars 1 and 2, rigidly framed together by cross-bars 3 and 4 at convenient points intermediate the front and rear ends and a stubbleward offset portion comprising fore-and-aft bars 5 and 6 and transverse bars 7 and 8, rigidly uniting them to each other and to the fore-and-aft bars 1 and 2 of the longer fore-and-aft main portion 45 of the frame. The frame is mounted on caster-wheels 11 at opposite sides of the forward end of the main portion and 12 at opposite sides of the rear end, one at the stubbleward side of the offset portion and the other at the extreme grainward side of the main fore-and-aft portion. All these wheels should preferably be caster-wheels, for the reason that the structure is designed to be attached to a wagon A, located at the stubble-

ward side of the main fore-and-aft portion of 55 the frame and forward of the offset portion in the angle between the two, such wagon being designed to be drawn over the field by any convenient means and to constitute the means of propelling the machine over the field, the 60 husked corn being delivered from the machine into the wagon as the work proceeds. The machine is attached to the wagon by a link or draw-bar 15, connected to the forward side of the offset rear portion of the machine-frame and to the rear end of the reach 16 of the wagon-frame and also by a bar or arm 17, extending off rigidly from the reach 16 and braced thereto by the brace-bar 18, said arm 17 being made fast at its grainward 70 end to the stubbleward fore-and-aft bar 2 of the main frame. The entire rigid frame of the machine is thus connected for travel with the wagon-frame, and in turning corners or otherwise moving out of a straight path the 75 wheels which support the machine-frame are necessarily adapted to accommodate themselves to a curved path of travel which requires caster construction.

On the main fore-and-aft frame there is 80 mounted a mechanism for severing the stalks, a mechanism for detaching the ears from the stalks, a mechanism for separating the husks from the ears, and a mechanism for baling the husks. The particular construction of 85 these several mechanisms is not claimed in this application, and such mechanisms are shown in conventional form with chief attention to their relative positions rather than to their specific details. All these mechanisms 90 are driven by a motor B, which is conventionally shown in outline only, the drawing being intended to represent in such conventional way a gas-engine, on whose main crank-shaft B' there is a pulley B², which actuates a belt B³, passing around a pulley B⁴ on the main power-shaft C, which is a fore-and-aft shaft mounted on the fore-and-aft main frame and extending to the several mechanisms mentioned for communicating 95 power for driving them respectively.

The stalks are severed by a vibrating sickle 20, actuated by a pitman 21, connected to a crank 22 on the forward side of a crank-wheel 24, having rigid with it a beveled gear 25, meshing with a beveled gear 26 on the lower forward end of an inclined shaft 27 and at whose upper rear end there is fast a bev-

eled gear 28, which meshes with and is driven by a beveled gear 29 on the forward end of said main power-shaft C, suitable bearings for all the shafts mentioned being provided 5 in any convenient way not requiring particular description on the main frame or parts extended therefrom. The stalks being severed by the sickle, are designed to move rearward relatively to the machine as the latter 10 advances until their butt-ends pass over the transversely-extended and grainwardly-inclined picking-rolls D D D D, which are arranged in pairs, the two rolls of each pair revolving toward each other for carrying the 15 stalks down between them and snapping off the ears on the upper side of the rolls, the ears descending along the inclined rolls stubbleward into a trough E, in which they are engaged by the carrying-fingers f of an end- 20 less carrier F.

The shafts d of the rolls D are geared together by equal gears D' D' D' D', mounted on the grainward end of said shafts, respectively, and intermeshing successively the 25 shaft of the rearmost of said rolls having a beveled gear D² meshing with a beveled gear D³ on the lower end of a counter-shaft concealed in a bearing d³, at whose upper end said counter-shaft carries rigid with it a beveled gear D⁴, which meshes with a beveled gear D⁵ on the shaft C.

The endless carrier F delivers the ears over its upper end into a deflecting-spout 30, from which they are discharged upon the upper 35 side of the husking-rolls H H, which are of familiar type and are mounted in inclined position extending from a point underhanging the said spout down rearward to a point a little forward of the belt B³, where they are 40 connected together by two intermeshing gears H' and H² on their shafts, respectively. A short shaft H³ in the vertical plane of the shaft of the stubbleward of the two husking-rolls (see Fig. 4) has a universal-joint connection with the shaft of said roll, and a sprocket-wheel H⁴ on said shaft is driven by a chain H⁵ from the sprocket-wheel H⁵ on the shaft C for driving the husking-rolls.

At the lower end of the husking-rolls on the 50 upper side thereof the ears, stripped of the husks, are received by a chute or spout J, (see Fig. 1,) which conducts them transversely stubbleward into a trough K, in which an endless carrier L operates to carry the ears 55 up forwardly to the point above the upper end of the carrier F, where the ears are delivered into a transversely-extending delivering spout or chute M, which projecting stubbleward and extending downward overhangs 60 the box of the wagon which receives the ears from said spout.

The two carriers F and K have their upper 65 shafts f' k', respectively, provided with sprocket-wheels F' K', and a chain N, passing around the sprocket-wheel K' and around

a retaining-wheel F², is deflected inward about the sprocket-wheel F', with which it is held in positive engagement by said retaining-wheel F², and thereby drives the wheel F' in the opposite direction from the wheel K', as is necessary for proper direction of travel of the carriers F and K. Power for driving both these carriers is derived from the shaft u², hereinafter described, by means of a chain F³ passing about the sprocket-wheel f⁴ on the shaft u² and around the sprocket-wheel f³ on the shaft f'.

Underneath the husking-rolls H H a hopper S is arranged to receive the husks, said hopper having its ends converging to the mouth S', through which the husks are delivered into a baling-chamber T, which extends horizontally underneath the main frame. A follower U operates in the baling-chamber, reciprocating from a point forward of the mouth S, past under said mouth to pack the husks as they are delivered into the rear portion of the baling-chamber. This follower is reciprocated by a pitman U', connected to it and to a crank-wrist u' on a gear-wheel u², which is fast on a counter-shaft u², having suitable journal-bearings on the frame, said gear being meshed with a pinion U³ on a counter-shaft u³, which has also a beveled gear U⁴ meshing with a beveled pinion U⁵ on a vertical shaft u⁵, at whose upper end there is a second beveled pinion U⁶, meshing with a beveled gear U⁷ on the shaft C.

The particular construction of the baling-chamber and details of means for securing and removing the bales are not designed to be claimed herein and are not fully shown nor further described.

We claim—

1. In a corn-gatherer, in combination with a frame having supporting-wheels and means for attaching it to draft appliances, stalk-cutting mechanism, ear-detaching mechanism and husking mechanism mounted on the frame successively one behind another; a motor mounted on the frame in the rear of all said other mechanisms, and a fore-and-aft power-shaft extending forward from the motor and operatively connected with said other mechanisms for driving them.

2. In a corn-gatherer, in combination with a frame having wheels on which it may be mounted for travel and means by which it may be attached to a wagon for drawing it over the ground, stalk-severing mechanism, ear-detaching mechanism and husking mechanism mounted on the frame one behind another, the frame having a portion offset stubblewardly from said detaching, severing and husking mechanisms, and a power-generator mounted on said offset portion.

3. In a corn-gatherer, in combination with a frame having wheels on which it is mounted for travel and means for attaching it to draft appliances, stalk-severing mechanism, ear-

1 picking mechanism, husking mechanism and
2 husk-baling mechanism, all said mechanisms
3 being mounted on the frame in the fore-and-
4 aft path of the stalk-gathering devices, and a
5 motor for driving all said mechanisms also
mounted on the frame.

6 4. In a corn-gatherer, in combination with a
7 frame having wheels on which it is mounted
8 for travel and means by which it may be at-
9 tached to a wagon for drawing it over the
10 ground, stalk-severing mechanism, ear-de-
11 taching mechanism and husking mechanism
12 mounted on the frame one behind another,
13 the frame having a portion offset stubble-
14 wardly from the fore-and-aft line of said
15 severing, detaching and husking mechanisms;
16 a power-generator mounted on said
17 offset portion, the means for attaching the
18 wagon to the frame for drawing it being
19 adapted for locating the wagon in the angle
20 between said fore-and-aft portion and said
21 offset portion of the frame directly forward
22 of the motor-supporting portion thereof.

23 5. A corn-gathering machine comprising a
24 frame provided with wheels for supporting it
25 in travel, having a fore-and-aft extending
26 portion and a stubblewardly-offset portion;
27 stalk-severing, ear-detaching and husking
28 mechanisms mounted one behind another on
29 said fore-and-aft portion; a wagon located at
30 the stubbleward side of said fore-and-aft por-
31 tion and forward of the offset portion and
32 means connected with both said portions for
33 drawing the machine; a motor mounted on
34 said offset portion of the frame operatively
35 connected with the husking; picking and
stalk-severing mechanisms, and means for

delivering the ears from the husking mechanism
to the wagon.

6 40. A corn-gathering machine comprising a frame
7 having a fore-and-aft extending portion
8 and a stubblewardly-offset portion at
9 the rear end thereof; means for attaching a
10 wagon to said frame in the angle forward of
11 said offset portion and stubbleward of the
12 fore-and-aft extending portion; stalk-sever-
13 ing, ear-detaching, husking and ear-deliver-
14 ing mechanisms, and a motor for driving
15 them mounted on said frame, and caster-
16 wheels on which said frame is carried during
17 travel.

7 45. A corn-gathering machine comprising a
8 rigid frame consisting of a fore-and-aft portion
9 and a stubblewardly-offset portion at
10 the rear thereof; means for attaching a wagon
11 thereto for drawing it in the angle between
12 said stubblewardly-offset portion and said
13 fore-and-aft extending portion; a motor
14 mounted on the stubblewardly-offset portion;
15 ear-detaching and husking mechanisms
16 mounted on the fore-and-aft extending portion;
17 means for delivering the ears stubble-
18 wardly from the husking mechanism and
19 connections from the motor for driving all
20 said mechanisms.

21 In testimony whereof we have hereunto
22 set our hands, at Chicago, Illinois, this 7th
23 day of March, 1906.
